Inventor

Joseph L. Viscount

By his Attorney,
Wilbur M. Stone

UNITED STATES PATENT OFFICE.

JOSEPH L. VISCOUNT, OF NEW YORK, N. Y., ASSIGNOR TO SNYDER & BLACK, INCORPORATED, OF NEW YORK, N. Y., A CORPORATION OF NEW YORK.

DISPLAY DEVICE.

Application filed November 27, 1926. Serial No. 151,033.

This invention relates to display devices and has for its object to provide a device of the character specified, simple in construction, economical to manufacture and 5 effective and reliable when erected for use.

To these ends and others which will appear later herein, my improvements comprise features illustrated in their preferred embodiment in the drawing accompanying 10 this specification, wherein:

Figure 1 is a front elevation of my improved device spread out flat, in condition for stacking and shipping. Fig. 2 is a front perspective view of the device erected for 15 use. Fig. 3 is a front elevation, spread out flat, of a modified form of my device. Fig. 4 is a front perspective of the modifications of Fig. 3, erected for use. The scale of Figs. 1 and 2 is the same and the scale of 20 Figs. 3 and 4 is the same, but the scale of Figs. 3 and 4 is about half that of the earlier figures.

My improved device is preferably made from cardboard and is formed integral. 25 The lower edge 3 of the device is preferably in one line to form a base and the upper edge 4 may have some fanciful or ornamental contour as shown.

The body 2 of the device is provided with 30 at least four folding score lines as 5, 6, 7 and 8, extending from top to bottom and dividing the device into at least five panels. While these score lines are illustrated as normal to base 3, it is obvious that they or 35 some of them may be inclined relatively to said base, as well known in the art.

In Figs. 1 and 2 the device is severed transversely at 9, across midpanel 10 and across the opposite adjacent panels 11 and 40 12. Also near the upper end of said midpanel, transverse score line 13 is provided extending across said midpanel. The opposite ends of said score line 13 are connected by similar score lines extending obliquely 45 downward and outward across panels 11, 12 to meet the outer ends of severing line 9, where they meet score lines 5 and 8, all respectively.

Said midpanel is thus divided into three 50 panel sections, 16, 17 and 18, and panel section 17 is connected at its lateral edges to opposite adjacent panels 11 and 12 by sub-panels 14, 15 respectively. Then, by folding panels 11 and 12 forwardly on lines 6 and 7 and swinging the lower edge of panel

section 17 forwardly and folding opposite outer panels 19, 20 backwardly, the device is erected for display, see Fig. 2, with mid-panel section 18 standing forwardly relatively to the other sections of said mid-panel. 60

Directing attention now to Figs. 3 and 4, transverse severing line 21 extends laterally only to about midway the width of adjacent panels 22, 23 and the opposite ends of 65 said severing line 21 are connected with the upper edges of said panels 22, 23 by score lines 24, 25 respectively. These score lines 24, 25 are preferably parallel. Then, by folding the device as shown in Fig. 4, upper mid-panel section 26 is caused to stand 70 forwardly relatively to lower section 27.

There is thus provided a display device simple in construction and effective when 75 erected.

I claim:

1. A display device formed from one piece of sheet material comprising five panels articulated on lines extending from top to bottom, the mid-panel being divided transversely into a plurality of panel sections, one of 80 said sections standing forwardly relatively to another panel section, said forwardly standing panel section being connected at its lateral edges to those panels next adjacent 85 said mid-panel by means of sub-panels respectively, formed from said adjacent panels.

2. A display device formed from one piece of sheet material comprising five panels articulated on lines extending from top to bottom, the mid-panel being divided transversely into a plurality of panel sections, one of 90 said sections standing forwardly relatively to another panel section, said forwardly standing panel section being connected at its lateral edges to those panels next adjacent 95 said mid-panel by means of sub-panels respectively, formed from said adjacent panels, the lines of articulation of said sub-panels with said forwardly standing panel being inclined forwardly, from top to bottom. 100

3. A display device formed from one piece of sheet material comprising five 105 panels articulated on vertical lines, the mid-panel being divided transversely into a plurality of panel sections, one of said sections standing forwardly relatively to another panel section, said forwardly standing panel 110

section being connected at its lateral edges to those panels next adjacent said mid-panel by means of sub-panels respectively, formed from said adjacent panels, the lines of articulation of said sub-panels with said adjacent panels extending angularly across said adjacent panels respectively and con-

verging toward the top whereby said forwardly standing panel is inclined from top to bottom.

10

In witness whereof, I hereby affix my signature this 24th day of November, 1926.

JOSEPH L. VISCOUNT.
